UNITED STATES PATENT OFFICE.

ERNEST L. GALE, JR., OF YONKERS, NEW YORK.

CONVEYER.

1,138,100.

Specification of Letters Patent.

Patented May 4, 1915.

Application filed April 16, 1914. Serial No. 882,156.

To all whom it may concern:

Be it known that I, ERNEST L. GALE, Jr., a citizen of the United States, residing at Yonkers, in the county of Westchester and State of New York, have invented a new and useful Improvement in Conveyers, of which the following is a specification.

My invention relates to improvements in endless conveyers and has a general application to endless conveyers of the passenger or freight carrying type, traveling in a horizontal, inclined or vertical plane.

One of the objects of the invention is to provide an endless conveyer, having laterally movable carriers or treads, whereby objects conveyed thereby are landed or discharged therefrom to the side of the conveyer.

Another object of the invention is to provide a conveyer operable automatically to discharge laterally at one or more points or side landings in its path of travel.

Still another object of the invention is to provide a selective control system, whereby each carrier or tread can be independently controlled automatically to discharge only at the desired one of a number of landings.

Another object of the invention is to provide an endless conveyer operable to discharge objects conveyed thereby at one or more points at one or both sides of the conveyer, and in a longitudinal direction, making the conveyer in effect, a "three way discharge conveyer."

Still another object of the invention is the provision of a hand rail capable of lateral movement with the carriers or treads.

A still further object of the invention is to provide an escalator capable of discharging the passengers to the side thereof, without requiring a step to be taken by the passenger from the escalator to the landing, which is effected by the present invention by providing transversely movable treads which will slide the passenger therefrom to the landing.

Other objects of the invention will appear more fully hereinafter, the novel combinations of elements and arrangements of parts being pointed out in the appended claims.

Referring now to the drawings, Figure 1 shows a conveyer of the step type, the same being more or less diagrammatic; Fig. 2 is

a diagrammatic plan view of a portion of a conveyer having a plurality of landings on each side thereof, and an end landing; Fig. 3 shows a portion of a carrier, etc., and a stationary landing; Fig. 4 shows in detail a front elevational view of a truck having two laterally movable carriers, and an additional carrier stationary on the trucks, also various controlling mechanism for the laterally movable carriers, together with two movable landings; Fig. 5 is a plan view of a portion of Fig. 4; Fig. 6 shows a side elevational view of a portion of Fig. 5, and also an electrically operated cam; Fig. 7 shows an enlarged detail view of rollers, etc., shown in Fig. 4; Fig. 8 is a part sectional plan view of certain portions of Fig. 7; Fig. 9 is an enlarged plan view of the deflecting track system as arranged at the landings D, E and F, shown in Fig. 2, together with various other electrical apparatus; Fig. 10 is a modified construction for effecting the lateral movement of the carrier; Fig. 11 shows a hand rail such as is associated with each tread; Fig. 12 shows a carrier of modified construction, more particularly adapted to carry loose material; Fig. 13 shows a carrier or tread of modified construction, the same being adapted to move laterally over the side of the conveyer.

Referring now to Fig. 1, truck frames 1 are provided with wheels 2, which co-act with tracks or ways 3 and 4. These tracks are of a well known construction and are therefore illustrated diagrammatically. The trucks are connected together in a well known manner, as for example by suitable driving chains or links 5, to form an endless carrier. The chains are driven in a well known manner, as for example by means of sprocket wheels 6, which are driven by a set of gears 7 driven by any suitable source of power.

Each truck is provided with two laterally movable carriers or treads 8 and 9 (see Fig. 4) which I have shown in the form of endless belts. The carrier and particularly the working surface thereof, may be made of leather, rubber, sheet steel, or in fact any of the well known carrier or treads having flexibility, may be employed. These belts are carried by rollers 10 and 11, respectively, and additional sets of rollers 12 and 13 are

provided to prevent sagging of the belts. The rollers 10 and 11 are carried by shafts 14 and 15 respectively, said shafts being suitably journaled in bearings 16 and 17. 5 The carriers 8 on the left side of the trucks are adapted to land or discharge objects conveyed thereby to the left side of the conveyer, each carrier being independently controlled as hereinafter described automatically 10 to discharge at any one of the plurality of landings A, B or C. The carriers 9 are controlled in a like manner to discharge to the right side of the conveyer, to any one of the landings D, E or F. These landings 15 as illustrated in Figs. 2 and 4, are in the form of belt conveyers which are operating at right angles to the main conveyer, such an arrangement being obviously for freight service, etc. When my conveyer is 20 adapted for passenger service, stationary landings are provided, such as illustrated in Fig. 3, the said landings being cut away as shown at 18, so that the top surface 18' thereof is flush and in close proximity with 25 the tread surfaces of the conveyer.

A third tread or carrier 19 is fixed stationary on the truck frame, this carrier being adapted to discharge at the end of the run of the conveyer onto a landing G. It 30 will be here noted that each one of the trucks 1 being provided with three carriers, 8, 9 and 19, makes the conveyer in effect a "three-way discharge conveyer." A hand rail 64 is provided for each carrier, and comprises an upright or standard 65 which is suitably secured to the carrier. This standard may be in the form of a wooden ornamental panel having the hand rail portion 64 formed at the top, for the hands of 35 the passenger. These panels may be of the same length as the carrier shown in Fig. 1, the same of course being movable laterally with the carrier and the passenger can therefore maintain a hold on the same during 40 such movement of the carrier to discharge the passenger. These rails are located at the right hand side of the carrier 8 and at the left hand side of the carrier 9 as shown in Fig. 11.

50 In order now to effect the discharge operation or lateral movement of the carriers 8 and 9, I associate with each carrier a block 20 (see Fig. 7) carrying a rod 21, which supports a roller 22. These rollers 55 travel between suitable tracks 23, which are positioned near the outer edge of the conveyer, and extend in alinement therewith as shown at 23'. At the first landing point, such as D for example, the tracks deflect 60 inwardly as shown at 24, and extend again in alinement with the conveyer as shown at 25. The rollers 22 will thus be deflected by the deflector track 24, and thereby cause a lateral movement of the carrier or tread 65 which movement thereof is equal to the

width of the tread surface as designated by the arrows b—b, which amount of movement thereof will effect the complete discharge of objects from said carrier. Guides 55 are attached to each truck frame, and engage slots 56 in the blocks 20, these guides serving to steady the said blocks and prevent buckling of the belt, as the rollers 22 are deflected. The rollers 22 after passing through the deflector track 24, follow the 70 inward tracks 25 which extend in alinement with the conveyer to the end of the run thereof, whereupon they extend to the return run of the conveyer, and again deflect as shown at 26 to the outer edge designated 75 27 of the conveyer, and from there extend continuously through the return run of the conveyer to the top run which is designated 80 23'. Although I describe these tracks as extending through the top run 23' and return or bottom run 27 of the conveyer, the 85 said tracks if desired may be discontinued from the deflector 26 to the approach to the top run 23'. It is desirable to start the tracks at the approach to the top run, since 90 this point is the receiving end of the conveyer, and the treads will therefore be steadied throughout their entire travel on the upper or working run of the conveyer. Tracks 28 and 29 extend from the landing 95 D to landing E and F respectively, and deflectors 30 and 31 are positioned at the said landings, respectively, each deflector leading to the inner tracks 25. These deflectors 24, etc., may be independent sections, so 100 that they may be placed at any point along the run of the conveyer where it is desired to discharge. The rate of discharge or lateral movement of the treads or carriers may be varied by changing the angle at 105 which the deflectors are set.

In the modified construction shown in Fig. 10 for effecting a lateral movement of the carriers, a toothed rack 32 is provided, which rack is positioned at each landing. 110 The rack is adapted to be engaged by a pinion 33 which rotates the shaft 16, through a sprocket and chain connection 34, which is driven by a bevel gear connection 35, from the pinion 33. The racks 32 of course 115 are made of a sufficient length to effect a complete discharge movement of the carrier.

The selective control system whereby each carrier can be controlled automatically to discharge only at the desired one of the 120 landings D, E or F, comprises manually operable switches 36 and 37, associated with each carrier, each switch comprising a contact shoe 38 and 39, which are carried by rods 40, 41, respectively, which extend upwardly through the truck frame 1. These shoes are normally held out of contacting position from contact strips 42, 42' and 43, 43', by springs 44. Pivoted levers 45 and 46 are provided with cam faces 45' and 46', 130

which upon the movement of the levers to a longitudinal position move the shoes 38 and 39, respectively, into a position to contact with the said strips. The shoe 38 is of a width sufficient to span the contact strips 42 and 42', and the shoe 39 is of a width sufficient to span both pairs of strips as seen in Fig. 9. The strips 42 and 42' are positioned at the first deflector 24, in a position to be engaged by the shoe 38 and 39 and the strips 43, 43' are positioned at the second deflector 30, and offset from the strip 42, 42' to be engaged by the shoe 39 only. Cams 47 and 48 are normally held in an inoperative position by springs 49, and are actuated to an operative position by electromagnets 50 and 51, respectively. These cams when in their operative position are adapted to coat with rollers 52, carried by a member 53, which moves vertically in a slot 54 in the rod 21, thereby raising the roller 22 to clear the top of the deflector track at the point 24', so as not to be deflected by the same. The electromagnets 50 and 51 receive current from a suitable source of supply designated + and -.

The operation will now be described, and since the method of control for the carriers 8 which discharge to the left, and the carriers 9 which discharge to the right, is similar, a description of one set of carriers will therefore suffice for both sets. Taking for example the carrier 9 on the right hand side of the trucks, if it is desired that all these carriers shall discharge at the first landing D, the switches 36 and 37 are left in their normal position as shown, whereby the shoes will not contact with the strips 42, 42', and the cam 47 therefore will remain in its inoperative position as shown, and the rollers 22 will thus be deflected by the first deflector 24, thereby effecting the discharge operation or lateral movement of each carrier at the landing D. If now it is desired that alternate carriers be discharged at the landing E, and the others at landing D, the switches associated with the latter trucks will then be left in their normal position as shown, and the carriers carried by such trucks will therefore discharge at the landing D as above described. The switch 36 of alternate trucks are actuated, thereby shoving the shoes 38 into position so as to contact with the contact strips 42, 42'. As each of these shoes 38 contact with the strips 42, 42', a circuit is completed for the electromagnet 50, as follows: From the + conductor to contact strip 42, through the shoe 38 to contact strip 42', conductor 57, through winding of electromagnet 50, and conductor 58 to - line. The electromagnet thus being energized will actuate the cam 47 to its operative position, whereby the roller 52 will strike the same, causing the upward movement of the rollers 22 so as to clear the top of the deflector 24 at the point 24'. The contact strips are of such a length and are so positioned at the deflector 24, as to cause the electromagnet 50 to maintain the cam 47 in operative position just long enough to permit the same to effect the upward movement of the rollers 22 at the point 24', whereupon the shoes 38 ride off the said contact strips, causing the deenergization of the electromagnet 50, and the rollers 22 will drop between the tracks 28. Since now the shoes 38 can not contact with the contact strips at the landing E, the cam 48 will of course remain inoperative, and the rollers 22 of the said alternate trucks will therefore be deflected by the deflector 30, this causing the discharge operation of said alternate treads at the said landing E.

If it is desired to discharge to the three landings D, E and F, the carriers discharging in consecutive order, that is for example, as illustrated in Figs. 2 and 9, wherein all carriers designated 9' discharge at landing D, the carriers 9'' at landing E, and the carriers 9''' at landing F, the method of control is as follows: To effect the discharge operation of all carriers 9' at landing D, the switches 36 and 37 associated with carriers 9' will be left in normal position as shown, and the rollers 22 associated with all carriers designated 9' will be deflected by the deflector 24 and thereby effect the discharge operation of said carriers 9' at the landing D. To effect the discharge operation of the carrier 9'' at landing D', the switches 36 associated with each carrier 9'' are actuated, which will effect in a manner hitherto described, the discharge operation of carriers 9'' at the landing E. To effect the discharge operation of carriers 9''' at the landing F, the switches 37 associated with the carriers 9''' are actuated. The shoes 39 will contact with the contact strips 42 and 42' at the landing D, and also contact strips 43, 43' at the landing E, thereby effecting the lifting of the rollers 22 to clear the deflectors at the points 24' and 30' and consequently these rollers drop between tracks 30 and are deflected by the deflector 31. Thus the discharge operation of the carriers 9''' will be effected at the landing F.

It will be seen that each one of the treads or carriers 8 and 9 can be independently controlled, automatically to discharge at only a desired landing of a plurality of landings; and furthermore it will be seen that I have provided a conveyer operable to discharge to a plurality of side landings simultaneously.

It will be further noted that the laterally movable treads will move the passengers laterally in the plane of movement of the conveyer, and discharge said passengers therefrom onto the landing. The danger of

tripping or of drawing in of wearing apparel is entirely eliminated, since the landing or floor plates as shown in Fig. 3 is flush with the tread surface and in close proximity thereto.

The landings D, E, F, may all be in substantially the same plane, as would be in the case of a horizontally movable endless conveyer, or they may be at different elevations, as in the case of an inclined conveyer, illustrated in Fig. 1.

It is obvious that the conveyer may be constructed with a single laterally movable tread for each truck, or with two of said treads, such as 8 and 9, the middle tread 19, being eliminated in either case.

Another important feature of the present system particularly in its use for passenger service, resides in the provision of a traveling way by means of which passengers may be transported past all the landings (that is to say the path for the transportation of the passengers is continuous or of unbroken continuity), and yet provision being made to effect a positive discharge of a passenger at any of the landings. This feature will be readily appreciated since it will be seen that with the present system there are no obstructions whatsoever at the landings such as shunts, as now commonly used to effect a side discharge, which shunts form a break in the path of travel of the passenger, requiring a passenger desiring to go past the landing to step off and again onto the traveling way. In the way of giving a concrete example in the way of illustrating this important feature of the invention, we will take a single moving way connecting four floors, now it will be seen that a passenger desiring to go from the first to the fourth floor will have a passage which is continuous or of unbroken continuity between these floors, the passenger not having to step off of and again onto the traveling way at the second and third floors; and furthermore, it is seen that a positive discharge of a passenger at any of the intermediate floors, such as the 2nd or 3rd floors, can be effected if so desired.

50 A conveyer having trucks each provided with three carriers, as disclosed in Fig. 4, may be used to a great advantage on a dock or the like, where it is desired to discharge freight, etc., at one or more points on one 55 or both sides thereof, and also at the end of the dock also. Thus with the arrangement shown in Fig. 4, this can be accomplished, since each of the carriers 8 and 9 can be independently controlled to discharge at any 60 desired landings on the left and right side respectively of the conveyer, and the middle carriers 19 discharging at the end of the conveyer. By means of switches 36 and 37 a despatcher standing at the receiving end 65 of the conveyer, can control each carrier to

discharge at any of the desired landings. Of course it will be seen that by removal of the deflector tracks 24, 30 and 31, all three carriers 8, 9 and 19 will discharge at the end of the conveyer.

The switches 36 and 37 can be so constructed and so arranged that a passenger can conveniently actuate the same by foot or hand and thereby control the particular carrier on which he is standing to discharge at any 75 desired landing. A suitable number of these switches, etc., are provided according to the number of landings, to be discharged at.

An application of the present invention to a conveyer adapted to carry loose material, such as coal, etc., is illustrated diagrammatically in Fig. 12, in which case the trucks 1 are provided with a plurality of buckets 60, which are hinged at 64, to a suitable supporting member 62, carried on rollers 85 11'. The buckets being thus hinged will permit the same to travel around rollers 11' and thereby effect the discharge of the contents of the buckets.

In the modification shown in Fig. 13, a member 60' provided with rollers 61 supports the tread or carrier 62, the ends of which are fixed at 63. The member 60' is adapted to be moved laterally over the side of the conveyer, moving the tread therewith 95 in a manner to effect the discharge therefrom of an object carried thereby.

It is obvious that various modifications to the mechanism herein disclosed will suggest themselves to those skilled in the art, 100 one particular instance being in the case of the mechanism for controlling the operation of each carrier to discharge at only the desired landing. It will readily be seen in this instance that instead of lifting the rollers 105 22 at the points such as 24', 30', etc., the same can be controlled by track switches located at the said points, with the provision of suitable means such as an electromagnet for controlling the operation of the same, 110 and said track switches can be arranged so that they will normally prevent the rollers from entering the deflector tracks and when actuated cause the rollers to enter the particular deflector track associated with the 115 operated track switch.

I desire therefore not to be limited to the precise construction and arrangement of parts as herein disclosed.

What I claim as new and desire to protect 120 by Letters Patent of the United States is:—

1. A three-way discharge conveyer comprising means for discharging objects conveyed thereby to both sides of the conveyer, and longitudinally at the end thereof and 125 a trackway for the conveyer forming an upper and lower run therefor.

2. A three-way discharge conveyer comprising means for simultaneously discharging to both sides of the conveyer and longi- 130

tudinally at the end thereof and a trackway for the conveyer forming an upper and lower run therefor.

3. A longitudinally movable conveyer comprising means for simultaneously discharging objects conveyed thereby at one or more points at one or both sides thereof, and longitudinally at the end thereof and a trackway for the conveyer forming an upper and lower run therefor.

4. An endless conveyer comprising means for automatically discharging objects conveyed thereby laterally to both sides thereof, and longitudinally at the end thereof and a trackway for the conveyer forming an upper and lower run therefor.

5. The combination of an endless series of carriers, a landing, and means for moving the carriers laterally when opposite said landing, to effect a discharge from the carriers.

6. The combination of an endless series of independent carriers, having a lateral movement to effect a discharge therefrom, a plurality of landings, means for moving the carriers longitudinally and laterally, and means for controlling the carrier to discharge at the desired landing.

7. The combination of an endless series of continuously movable carriers, having a lateral discharge movement, a plurality of side landings, means for moving the carriers longitudinally and laterally, and means for controlling the carriers to effect a discharge at all of the landings simultaneously.

8. The combination of an endless series of continuously movable carriers having a lateral discharge movement, a plurality of side landings, means for moving the carriers longitudinally and laterally, and means for effecting the discharge of each carrier only at a desired landing.

9. The combination of an endless series of continuously movable carriers having a lateral discharge movement, a plurality of side landings, and means for controlling each carrier automatically to discharge only at the desired landing.

10. In an escalator, the combination of a series of independent laterally movable treads, a side landing, and means for moving the treads laterally when opposite said landing.

11. In an escalator, the combination of a series of independent laterally movable treads, a side landing, and means for moving the treads laterally at a predetermined rate of speed when opposite said landing.

12. In an escalator, the combination of a series of trucks each having a laterally movable tread, a side landing having its tread surface flush with the first named treads and in close proximity thereto, and means for moving the first named treads laterally when opposite said landing.

13. In an escalator, the combination of a

series of independent laterally movable treads, a side landing, and means for automatically moving the said reads laterally when opposite said landing.

14. In an escalator, the combination of a series of independent treads movable laterally and in the plane of movement of the escalator, and a side landing having its tread surface flush with the first named treads and in close proximity thereto.

15. An escalator comprising a tread, means for moving the tread continuously in an endless path and means for moving the tread laterally.

16. An escalator comprising a tread, means for moving the tread continuously in an endless path, and means for moving the tread laterally a predetermined amount.

17. An escalator comprising a tread, means for moving the tread continuously in an endless path, and means for moving the tread laterally a predetermined amount and at a predetermined rate of speed.

18. In an escalator, a tread having right and left hand movements, means for moving the tread continuously in an endless path, and automatic means for actuating the tread to effect said right and left hand movements thereof.

19. In an escalator, a tread movable laterally to effect a discharge therefrom, and automatic means for actuating the tread to effect said movement thereof.

20. In an escalator; a sectional tread having a predetermined amount of movement to effect a discharge therefrom, and automatic means for moving the tread a predetermined amount.

21. An escalator comprising a tread movable continuously in a general direction, and electrically controlled means operable automatically to effect a lateral movement of the tread.

22. In an endless conveyer, a carrier movable in paths having angular relation, and means comprising a coacting deflector track for effecting one of the said movements of the carrier, the said movement being in a horizontal plane.

23. In an endless conveyer, a carrier movable in paths having angular relation, and means comprising a coacting deflector track controlled electrically to effect one of the said movements of the carrier at any desired one of a number of points.

24. In an endless conveyer, a carrier having movements simultaneously in endless paths, one of which is in a horizontal plane and in angular relation to the other path.

25. In an endless conveyer, a carrier having movement simultaneously in endless paths which are in angular relation, and means for effecting the said movements of the carrier.

26. In an escalator, the combination of a

- series of independent treads, means for moving the treads continuously, means for steadyng the treads, and means for moving the treads laterally at a desired point.
- 5 27. In an escalator, the combination of a series of independent laterally movable treads, means for moving the treads continuously in an endless path, a movable hand rail and means for moving the treads and 10 handrail laterally at a desired point.
28. In an escalator, the combination of an endless series of treads having a lateral movement to effect a discharge therefrom, and a sectional hand rail movable therewith.
- 15 29. The combination with an escalator, of a side landing, and treads for the escalator, operable to effect a positive discharge of a passenger therefrom onto the landing without a step being taken by the passenger.
- 20 30. An escalator comprising an endless series of independent carriers, operable to effect a positive discharge of passengers therefrom to one or simultaneously to both sides of the escalator.
- 25 31. An escalator comprising an endless series of independent trucks, and means associated with the trucks for effecting a positive discharge of conveyed objects at a desired point or points on one or both sides 30 of the escalator.
32. An escalator comprising a truck having a tread associated therewith, means for moving the truck longitudinally, and means dependent on the longitudinal movement of 35 the trucks for effecting a lateral movement of the tread.
33. An escalator having a sectional tread surface movable continuously in an endless path and in another path which is in a horizontal plane and in angular relation to the 40 first named path.
34. The combination with an escalator, of landings at both sides of the escalator, and treads associated with the escalator, operable 45 to effect a positive discharge of passengers therefrom onto both of said side landings.
35. In an escalator, a tread movable transversely to effect a discharge therefrom, and automatic means for actuating the tread to 50 effect the transverse movement thereof.
36. In an escalator, a tread movable continuously in an endless path, and automatic means for actuating the tread to effect a transverse movement thereof.
- 55 37. The combination of an endless series of independent carriers, a plurality of discharge points, means comprising a coating deflector rail at each discharge point operable to effect a discharge from the carriers, 60 and means for controlling each carrier, to effect a discharge therefrom only at a desired landing.
38. The combination with a number of conveyers operating at different angles, one 65 of the conveyers comprising carriers having lateral movement to effect a discharge therefrom to the remaining conveyers.
39. The combination with a number of conveyers, one of the conveyers comprising an endless series of carriers having a lateral movement to effect a discharge therefrom, and means for controlling the carriers to discharge to any of the desired conveyers.
40. A conveyer comprising a sectional carrying surface, movable in an endless path, and means for effecting a transverse movement of the said sections, to effect a discharge therefrom.
41. A conveyer comprising a series of connected sections movable as a unit in an endless path, and means for automatically discharging objects from the sections by moving the same transversely.
42. An escalator comprising an endless series of independent transversely movable treads, a number of side landings, means operable automatically to move the treads transversely, and means operable from each tread to control the said automatic means to effect such transverse movement of each tread only at a desired landing.
43. The combination with a number of landings, and means comprising a continuously movable tread for effecting a discharge of a passenger at any of the landings, the said tread presenting a path for the transportation of a passenger which is continuous or of unbroken continuity.
44. The combination with a plurality of landings, a conveyer forming a traveling way for the transportation of a passenger past said landings, the said way being flush with the landings and means for effecting a positive discharge of a passenger at any landing.
45. The combination with a number of landings, an escalator forming a traveling way for effecting transportation of a passenger past all the landings, and means for effecting a discharge of a passenger from the escalator at any landing.
46. The combination with a number of landings, a tread surface presenting a path for the transportation of a passenger past all the landings, and means for effecting a positive discharge of a passenger from the tread at any landing.
47. The combination with a number of landings, a traveling tread surface presenting a path for the transportation of a passenger past all the landings, and means operable automatically to effect a positive discharge of a passenger from the tread surface at any landing.
48. A conveyer comprising a sectional belt, means for moving the belt, and means comprising a track for effecting a transverse movement of the belt.
49. A conveyer comprising a series of belt sections, means for moving the sections con-

tinuously in an endless path, and means operable to effect a transverse movement of the sections.

50. A conveyer comprising a series of belt sections, means for moving the sections continuously in an endless path, and means operable to effect a transverse movement of the sections independently.

51. A conveyer comprising a series of belt sections, means for moving the sections, continuously in an endless path, and electrically controlled means operable to effect a transverse movement of the sections independently.

52. A conveyer comprising a series of belt sections, means for moving the sections, and electrically controlled means operable to effect a transverse movement of the sections independently at a desired point.

53. A conveyer comprising an endless series of belt sections, means for moving the sections, and means operable automatically to effect a transverse movement of any of the sections at any one of certain fixed points.

54. A conveyer comprising an endless series of belt sections, means for moving the sections, and means operable to effect a transverse movement of any of the sections automatically at any one of certain fixed points.

55. A conveyer comprising an endless series of belt sections, means for moving the sections, and means controlled electrically for effecting a transverse movement of any of the sections at any one of certain fixed points.

56. A conveyer comprising a sectional belt, means for moving the belt, and means comprising a coating track for automatically effecting a transverse movement of the belt.

57. A conveyer comprising a sectional belt, means for moving the belt, and means dependent on the movement of the belt for automatically effecting a transverse movement thereof.

58. An endless conveyer comprising purely mechanical means dependent on movement of the conveyer for effecting a lateral discharge, and selective controlling mechanism for effecting a discharge at a desired point or points.

59. An endless conveyer comprising purely mechanical means dependent on movement of the conveyer for effecting a lateral discharge, and selective controlling mechanism for effecting a discharge simultaneously at a plurality of points.

60. A longitudinally movable conveyer comprising purely mechanical means dependent on movement of the conveyer for effecting a lateral discharge to one or simultaneously to both sides of the conveyer.

61. A longitudinally movable conveyer comprising purely mechanical means dependent on movement of the conveyer for effecting a lateral discharge at a desired point or points on one or both sides of the conveyer.

62. A longitudinally movable conveyer comprising purely mechanical means dependent on movement of the conveyer for effecting a lateral discharge at one or simultaneously at a plurality of points on one or both sides of the conveyer.

In testimony whereof, I have signed my name to this specification in the presence of two subscribing witnesses.
